[57] **CLAIM**

The ornamental design for the panel carrier, as shown and described.

DESCRIPTION

FIG. 1 is a perspective view of the panel carrier showing my new design;

FIG. 2 is a front elevational view thereof;

FIG. 3 is a side elevational view thereof, the opposite side being a mirror image;

FIG. 4 is a rear elevational view thereof;

FIG. 5 is a top plan view thereof;

FIG. 6 is a bottom plan view thereof;

FIG. 7 is a rear perspective view of the panel carrier showing an alternative embodiment of my new design;

FIG. 8 is a front elevational view thereof.

FIG. 1

FIG. 2

FIG. 3

FIG. 4

FIG. 5

FIG. 6

FIG. 7

FIG. 8
